CLAIM

The ornamental design for a combined visor and novelty hang tag, substantially as shown and described.

DESCRIPTION

FIG. 1 is a top plan view of a combined visor and novelty hang tag showing my new design;

FIG. 2 is a front elevational view thereof;

FIG. 3 is a right side elevational view thereof;

FIG. 4 is a right side elevational view with a different hang tag; and,

FIG. 5 is a front elevational view thereof.

The broken line showing of a strap in FIGS. 1, 3, and 4, is for illustrative purposes only.
